UNITED STATES PATENT OFFICE.

HENRY PRICE BALL, OF NEW YORK, N. Y., ASSIGNOR OF ONE-HALF TO
SAMUEL INSULL, OF CHICAGO, ILLINOIS.

PERFORATING DEVICE FOR MUSIC-ROLLS.

No. 799,025.

Specification of Letters Patent.

Patented Sept. 12, 1905.

Application filed April 11, 1903. Serial No. 152,281.

To all whom it may concern:

Be it known that I, HENRY PRICE BALL, a citizen of the United States, residing at New York city, county and State of New York, have invented certain new and useful Improvements 5 in Perforating Devices for Music-Rolls, of which the following is a specification.

My invention relates to a machine for reproducing music-rolls, and comprises in its 10 construction a device responsive to the perforations in a music-strip, a second device for duplicating in one or more strips of paper the perforations of the music-strip, and synchronizing mechanism between the original 15 or master and the copies for perfecting in the copies any distortion of the spacing resulting from expansion or contraction of the master or variation in the feed thereof.

The present invention is designed to employ 20 the ordinary commercial music-rolls, such as may be purchased in open market as the originals, from which copies may be made, thus avoiding the inconvenience and expense of preparing what are known as "master-rolls."

In both the master and the commercial roll or copy thereof a definite proportion exists in the longitudinal spacing of the perforations unless through contraction or expansion the 30 sheet becomes distorted. When using a commercial roll as a master in duplicating, if it be assumed that it is free of such distortion and advanced uniformly, also that the interval between successive actions of the duplicating-punches is the same as that of the 35 punches employed in making the master, an absolutely perfect copy will be produced. If, however, as is usually found, the spacing of the perforations in the master-roll is disturbed by contraction or expansion of the 40 paper and the registering of the perforations therein with the tracker-ducks does not coincide with the action of the duplicating-punches the imperfections in the master will 45 be repeated and exaggerated in the copy and new errors included therein by the duplicating-punches unless the feed of the master is varied, as required, to restore exact synchronism between the opening of the tracker-ducks and the action of the coöperating 50 mechanisms.

The object of the present invention is therefore to mechanically duplicate in one or a number of copies the perforations of a commercial roll and at the same time automatically 55 correct in such copies any imperfections in the

spacing of the perforations which may be present in the master as a result of contraction or expansion of the paper subsequently to its being perforated.

60

A further object of the invention is to shorten the effective period of opening of the tracker-ducks by the perforations in the master, and thereby control the action of the responsive devices to prevent elongation of the 65 perforations in the copy beyond the length of the perforations in the master.

The accompanying drawings will serve to illustrate such a device as may be employed to carry my invention into effect. I wish it 70 understood, however, that I do not limit myself to the particular mechanism shown, as it will be obvious that many other mechanisms may be employed acting in substantially the same manner to produce the same result.

75

In the device which I have shown in the drawings the pneumatic mechanism employed is adapted to be operated by the pressure of the atmosphere, made effective through exhaust apparatus. I may, however, arrange the 80 mechanism so that it may be operated by air under pressure or by both exhaust and compressed air.

It will be understood that the device has its pneumatic mechanism, with the exception 85 of the bellows, repeated for each punch employed, also that there is a punch for each line of perforations in the master-roll.

In the drawings, Figure 1 is a plan view of the machine assembled. Fig. 2 is a detail sectional view of the changeable-speed gearing, forming part of the synchronizing mechanism, taken on the line $s^1 s^2$ of Fig. 1. Fig. 3 is a front view, partly in section, of the same, together with the feed-roll and its clutch. Fig. 4 is a detail view of the clutch controlling the rewind of the master-roll. Fig. 5 illustrates portions of a music-roll in which the distortion from contraction and expansion and the resulting relation of the perforations to the 90 normal spacing and the tracker-ducks are graphically indicated. Fig. 6 is a front view of the machine shown partly in section. Fig. 7 is a vertical longitudinal section taken on the line $s^7 s^7$ of Fig. 6. Fig. 8 is an enlarged detail sectional view of the pneumatics. Fig. 9 is a vertical longitudinal section taken on the line $s^9 s^9$ of Fig. 6. Fig. 10 is an enlarged detail view of the circuit-closer and its actuating device shown in Fig. 9. Fig. 11 is a view 100 in perspective of the machine with the circuits represented in diagram. Fig. 12 is a de-

tail view in perspective, showing the contact rings and connections of the rotary switch or circuit-controller forming part of the synchronizing mechanism; and Fig. 13 is a detail 5 sectional view of an audible signal.

In the drawings, 1 indicates the frame of the machine. Between parallel sections 2 2 thereof there is mounted a flanged roller or spool 3, carrying the perforated music-strip 4 which is to be duplicated, and which for 10 clearness of description, I shall hereinafter term the "master-roll." This roller or spool is so proportioned that the distance between the flanges or its effective length corresponds 15 to the width of the music-sheet and is commercially sold with it. At one end a stud or nipple of the roller finds a bearing and turns freely in the socket of a block 5, spring-seated in the frame, and at the opposite end the 20 roller is socketed to fit over and turn loosely on the projecting end of a shaft 6, as best shown in Fig. 4. The manner of placing the master-roll in position or removing it will be obvious.

25 In the operation of the machine the master-roll is advanced continuously by the feed mechanism now to be described.

A shaft 7, mounted in the frame, provides a bearing for the feed-roller 8, over which the 30 music-sheet runs as it is drawn from the spool 3 across the tracker-board 9. This roller, loosely mounted on the shaft, extends with it through the frame, Fig. 3, and has secured upon its end a bracket 10, which, being fixed, 35 rotates with the roller. A worm-wheel 11, fast on shaft 7, meshing with a worm 12, journaled in the feed-roller bracket 10, provides a driving connection between the shaft and the roller, and without motion in the 40 worm-gearing it will be evident that all parts rotate at the speed of the shaft. This condition exists in the absence of distortion in the master-roll or when the perforations are properly spaced in that portion of the strip 45 which is passing over the tracker-board. While at such times the feed-roller as geared will be driven from and rotated normally at the speed of the shaft 7, it has coöperating therewith changeable-speed gearing, which is 50 automatically controlled in a manner to be later on described, to vary the speed of the roller from that of the shaft, and thereby compensate for variations in the feed or in the spacing of the perforations as originally 55 cored—that is to say, if while thus driven the worm is caused to rotate the speed of the feed-roller will be either higher or lower than that of the shaft, depending upon the direction of rotation of the worm. If such rotation 60 is toward the left as viewed in Fig. 3, the speed of the feed-roller will be increased over that of the shaft, and if in the opposite direction—i. e., toward the right—there will be a corresponding decrease in the speed below 65 that of the shaft. The gearing for effecting

such independent rotation of the worm will now be described.

Fast on the worm-shaft there is a spur-gear 13, meshing with a similar gear 14, carried by a second shaft 15, also journaled in the 70 roller-bracket 10. A beveled pinion 16, fast on the opposite end of shaft 15, meshes with oppositely-disposed beveled gears 17 and 18, which are loosely mounted, one on the extension of the feed-roller and the other on the 75 shaft 7. Each of the gears 17 and 18 is provided peripherally with a friction-surface and a coöperating friction band-brake 19, whose ends are secured in the usual manner to an L-shaped lever 20, pivoted at 21 and operatively connected to the movable core of a solenoid 22. The brake-actuating solenoid 22 I shall hereinafter term the "high-speed controller" and 22 the "low-speed controller."

In order that the conditions under which 85 the changeable-speed gearing comes into action to vary the feed may be clearly understood, I will first refer, before describing the operation thereof, to the comparative illustration of portions of music-rolls shown in Fig. 90 5. As indicated therein, *a* represents a portion of the copy-blank in which perforations have been formed, and *b* the corresponding portion of the master-roll, distorted by expansion and shown at *c* as automatically adjusted so that the registering of the perforations therein with the tracker-ducks will coincide with the action of the punches indicated by the dotted lines *d d d*. The lines *d d d* indicate certain periods in the travel of the 95 sheet, when the punching mechanism is in position to respond instantly and reproduce in the copies the perforations of the master and the dotted circles *e e e* successive actions of the mechanism during the intervening intervals. The openings or ducts of the tracker-board are shown in connection with the perforations in the portions *b* and *c* of the master-roll.

If the master-sheet is mechanically perfect, 100 the centering of the perforations thereof over the tracker-ducks coincides with the cutting stroke of the punches. Under these conditions the speed-controlling solenoids, which are normally deenergized, will continue inactive, the gears 17 and 18 will run free in the brake-bands, and the entire gearing will rotate in the direction and at the speed of the shaft 7. If, on the other hand, the perforations in the master-roll fail to center at the 105 instant the punches are in position to act, as indicated in the portion *b* of the sheet, it is essential in order to avoid duplicating such distortion or error in the copies that the feed of the master be either increased or decreased 110 until exact synchronism is restored. Assuming, now, that through expansion the sheet is lengthened and there is delayed action in the 115 perforations centering over the tracker-board, as indicated at *b*, a slight increase in the speed 120 125

at which the sheet is advanced will obviously produce a synchronizing effect, and thereby compensate for such distortion of the sheet. Such a variation in the feed would result by 5 applying the brake to check the speed of the bevel-gear 17. Assuming this done, it will be seen that the bevel-pinion 16 while being carried around in the bracket at the speed of the shaft 7 will also rotate in the direction 10 indicated by the arrow in Fig. 3, and this motion transmitted through the gears 13 14 will cause the worm to rotate and climb the pinion on the shaft 7, thereby increasing the speed of the feed-roller over that of the shaft. Applying 15 the brake to the opposite gear 18 will manifestly produce the reverse rotation of the worm and a corresponding reduction in the speed of the feed-roller as compared to its driving-shaft, as might be required, for example, when a contracted portion of the 20 roll is passing over the tracker-board and the registering of the perforations with the tracker-ducts occurs prematurely or in advance of the cutting stroke of the punches. Applying 25 the brake to the opposite gear 18 will manifestly produce the reverse rotation of the worm and a corresponding reduction in the speed of the feed-roller as compared to its driving-shaft, as might be required, for example, when a contracted portion of the roll is passing over the tracker-board and the registering of the perforations with the tracker-ducts occurs prematurely or in advance of the cutting stroke of the punches.

Clutches 23 and 24—such, for example, as shown in Figs. 3 and 4—are employed in connection with the feed-roller and the spool of the master-roll. The clutch 23, which is normally thrown in by the spring 23^a, serves to 30 connect shaft 7 with the power, and thereby rotate the feed-roller to draw the music-sheet off the spool 3, as in the ordinary operation of the machine, while the clutch 24, which is normally thrown out by the spring 24^a, serves 35 when shifted to connect the spool 3 with the power for rewinding the sheet.

As mounted, the master-roll will be fed forward over the tracker-board continuously at a uniform rate of speed. The gearing for thus 40 advancing the sheet is shown in Figs. 6 and 7 and consists of a spur-gear 25, fast on the main or power shaft of the machine, which is continuously driven, the pinion 26 and bevel-gear 27 on the shaft 28, the intermeshing 45 bevel-gear 29 on the worm-shaft 30, and the worm-gearing 31, between this shaft and the feed-roller. This being in the nature of a reducing-gear, it will be seen that the speed of rotation of the feed-roller will be consider- 50 ably lower than that of the power-shaft, and when, therefore, the clutches are reversed to disconnect the feed-roll and connect the spool of the master-roll direct with the main shaft the rewind will be effected at an increased 55 speed, or the speed of the last-named shaft. A take-up roller 32 is mounted directly beneath the feed-roller in bearings 33 33, which are movable in guides, as shown in Figs. 6 and 7. These bearings are spring-supported 60 to maintain the roller in close contact with the feed-roller, from which it is frictionally driven, and also at the same time yield, as required, to allow for the varying diameter of the roller as the music-sheet is being wound 65 or unwound.

The pneumatic mechanism now to be described is responsive to the perforations of the music-strip and serves to control the action of the punches. The tracker-board forming part of this mechanism is provided 70 with a double series of openings or ducts, there being two ducts 34 34 for each line of perforations in the music-sheet, the arrangement being such that there is no action or response from the pneumatics until a perforation in the music-sheet registers with both tracker-ducts, as indicated at *f*, Fig. 5. While the use, therefore, of a double series of tracker-ducts instead of a single series lengthens the 75 actual time the tracker-ducts remain open 80 during the passing of a perforation, the effective period of opening is materially shortened, as will be apparent, and in consequence greater accuracy is insured in the spacing, and elongation of the perforations in the 85 copy over those of the master is avoided.

Separate passages 35 35 lead from each of the tracker-ducts to chambers beneath the diaphragms 36 36 of a pair of pneumatics 37 37, as shown in Figs. 7 and 8. Each of these 90 pneumatics consists of a vertically-movable stem 38, secured to or supported at its lower end on the diaphragm 36 and carrying a disk valve 39, which serves normally—*i. e.*, when the tracker-ducts are closed—to close the port 95 40 in the passage leading from the chamber 41 to the power-pneumatic 42. An exhaust-pressure is maintained in this chamber above the diaphragms by means of the power-bellow 43, Fig. 6, the pressure being regulated 100 and controlled by the pressure-limiting bellow 44 in a manner well known in the art. From the exhaust-chamber 41 a series of air-passages 45 lead to the power-pneumatics 42, there being one of such passages for each pair 105 of ducts in the tracker-board. Communication between each passage and the exhaust-chamber 41 is by way of the ports 40 40, controlled by the pneumatics 37 37. It will be observed that both valves or pneumatics must 110 be lifted to establish communication between the exhaust-chamber and the particular passage 45 in which they are located.

The operation of the pneumatics is as follows: When a perforation registers with a 115 pair of tracker-ducts, as at *f* in Fig. 5, air at atmospheric pressure enters the chambers beneath the diaphragms of the pneumatics and lifts the latter, opening the ports 40 40 and establishing communication between the ex- 120 haust and the power-pneumatic. Under the action of the exhaust the power-pneumatic collapses, and by means of suitable connections this movement is utilized to adjust a stop controlling the action of a punch and 125 also to close a circuit which includes the high and the low speed controllers of the changeable-speed gearing, as will be later on described.

The paper for the copies or copy-blanks, 130

supported in any suitable manner, passes between a pair of guide-rollers 46 46 and thence through a slot in the die-plate 47 to the feed-rollers 48 49. The copy-blank is advanced 5 step by step a definite distance by intermittent gearing consisting of a worm-wheel 50, fast on the feed-roller shaft, and a worm 51 on the shaft 52. The thread on the worm is perpendicular to its axis for the greater portion of its circumference, Fig. 9, and in rotating imparts an intermittent motion to the feed-roller, which in turn advances the paper step by step a definite distance, or one-twentieth of an inch for each revolution of the 15 shaft 28, carrying the punch-actuating eccentrics, from which the worm-shaft is driven by means of the bevel-gears 52^a 28^a.

I will now describe the punching mechanism, by which the perforations of the master 20 are duplicated in one or more copies.

Referring to Figs. 9 and 10, the punches 54 54, &c., are shown loosely mounted in a fixed bar or frame 55, extending transversely above the paper. Below the punches the die-plate 25 47 is movably mounted in guides depending from this frame and is formed with a series of openings with which the punches coöperate, there being one of such openings alined with each punch. The lower or cutting edge 30 of each punch rests normally in one of these openings in the die-plate in contact with the paper, which, as above stated, passes through a slot therein, and thus supported the punch is adapted to move up and down with the die-plate as the latter is reciprocated by means 35 of the eccentrics 56 56. The eccentric-shaft being continuously driven at a constant speed imparts a regular reciprocating motion to the die-plate, and in consequence, as will be seen, 40 the punch is in position to act on each up-stroke of the die-plate—that is to say, periodically—at regular intervals. The punch is caused to perforate the paper by being checked in its upward movement, while the movement 45 of the die-plate continues under the action of the eccentrics and forces the paper against the punch, the latter being thereby caused to cut its way through and form the perforation. To thus check the upward 50 movement of the punch, an adjustable stop-bar 58 is employed, the position of which is controlled by power-pneumatic 42, connected therewith by means of rod 59. The stop-bar is movably mounted in the frame directly 55 above the punch and is cut away about centrally of its length to form a recess, which normally centers over the punch, permitting a free up-and-down movement thereof. The upper end of the punch is formed with an enlarged head, which when the punch is in its 60 lowermost position enters and seats in a socket or groove of the frame clear of the stop-bar, which latter at such times is free to be adjusted by the action of the power-pneumatic. The headed end of the punch in seat- 65

ing in the socket of the frame checks its movement, while the die-plate continues downward, and thereby withdraws the punch from the paper after the perforation is cut therein, permitting the feed to act and advance the 70 paper step by step, as above described.

Having now described the devices responsive to the perforations in the music strip or master and the second device, by which such perforations are duplicated in one or more 75 copies, it only remains for me to describe the controlling device of the synchronizing mechanism, by which the feed of the master is regulated to cause the perforations thereof to register with the tracker-ducts at the instant the punches are in position to act. This device comprises a circuit-closer, a circuit-controller, and a switch coöperating with each of the speed-controlling solenoids of the changeable-speed gearing. The circuit-closer, 80 Figs. 9, 10, 11, consists of two contact members 60 61. The member 60, in the form of a post, is fixed on the punch-frame, and the second member or bell-crank lever 61 is mounted fast on a shaft 62, extending transversely above the stop-bars and journaled in uprights of the punch-frame. These members are normally separated, being thus held by a spring 63, which tends to force the contact-arm upward clear of the post and against 85 a stop-pin 64, by which its upward movement is limited. I preferably employ two sets of contact-arms and connect the members 61 thereof by means of the rod or bar 61^a. Each of the stop-bars is operatively connected with 90 this rod by having a gravity dog or pawl 65 pivoted thereon, with its hook end engaging the rod.

The operation of the circuit-closer will be readily understood. When one or a number 105 of note perforations of the master register with the tracker-ducts, the power-pneumatics connected therewith collapse and the corresponding stop-bars are thereby adjusted toward the right as viewed in Figs. 9 and 10, 110 causing the dogs of the stop-bars thus adjusted to swing the members 61 61 into contact with the posts and close the circuit. After the punches have acted to form the proper 115 perforations and in order that the circuit-closer may be in position to act on the next cutting stroke of the punches the circuit is made and broken during the movement of the stop-bar as it is adjusted toward the right by the collapse of the power-pneumatic. The 120 breaking of the circuit is effected by disengaging the dogs from rod 61^a, connecting the contact members 61 61, and the latter being free the springs act to return them to their normal position—*i. e.*, with the contact members separated. This disengagement occurs either at the instant or just before the stop bar or bars reach their limit of adjustment 125 and is effected by providing each dog with a lug 66 so relatively disposed as to engage and 130

ride up an inclined shoulder 67 of the punch-frame, thereby elevating the hook end of the dog above the rod and releasing the members 61 of the circuit-closer.

5 The circuit-controller, as shown in Figs. 11 and 12, is designed to direct the current to energize one or the other of the speed-controlling solenoids to vary the speed of the master, as may be required, or to cut out a solenoid after it is energized, and for this purpose it comprises three segments 68 69 70 and three rings 68^a 69^a 70^a, the segment 68 being connected with the ring 68^a, segment 69 with ring 69^a, and segment 70 with ring 70^a, as shown in Fig. 12. There are also contact-brushes 68^b, 69^b, and 70^b, one for each of the rings, and a similar brush 71 for the three segments, which latter are relatively assembled in ring form, but not in contact. The rings and segments are electrically insulated and mounted on a drum fast on the eccentric-shaft 28, which is driven from the main shaft by the spur-gear and pinion 25 26, above described.

25 As shown in Figs. 11 and 12, two of the segments of the ring 70 are substantially the same size, while the third is very much smaller, and in consequence during rotation the period of contact between the small segment and the brush will be momentary, while the period of contact between the brush and either of the other segments will be much longer.

The relation of the small segment to the eccentrics is such that it will come in contact with the brush 71 at the instant the eccentrics swing over the center at or near the lowest point of their throw, and if, as will appear later on, the spacing of the perforations in the master and the feed thereof are normal the passing perforations will at such times register with the tracker-ducks and the power-pneumatics will act to adjust the stop-bars and operate the circuit-closer; but, as will be more fully explained, there will be no action on the part of the speed-controlling solenoids and in consequence no variation in the feed of the master, as the mechanisms would then be operating in exact synchronism.

From the foregoing, it will be seen that if the registering of the perforations with the tracker-ducks does not coincide with the action of the punches, but occurs either before or after the small segment has made contact with its brush, an immediate response from the punch will be impossible, as it is actuated by the eccentrics periodically and the intervals between its actions are definite and uniform. In order to restore normal conditions, it would obviously be necessary to vary the feed of the master, and the changeable-speed gearing for doing this is controlled by mechanism now to be described, which, as will be seen, is brought into action whenever either of the larger segments makes contact with the

brush at the instant a perforation registers 65 with a tracker-duct.

As shown in Fig. 11, a generator or other source of electricity 72 is connected, through a wire 73, with the post 60 of one of the circuit-closers. A complete metallic connection 70 is provided for the passage of current from this post to the post of the second circuit-closer through the contact-arms 61 and the shaft 62, upon which they are mounted, the shaft being suitably insulated to prevent a ground or short circuiting through the machine. From the second post a wire 74 leads to the brush 71 of the sectional ring. In the connections between the controller and generator two automatic switches 75 76 are arranged, one of these switches 75 coöperating with the high-speed controller, or solenoid 22, which acts to increase the feed of the master, and the other, 76, with the low-speed controller, or the solenoid 22^a, by which the feed is reduced. The switches are identical in construction and operation and are described in detail in United States Patent No. 708,006, granted to me September 2, 1902. They consist, respectively, as shown, of two solenoids 90 77 78, separated a suitable distance and arranged one above the other. A core 79, common to both solenoids, has secured about centrally of its length a block of insulating material 80, carrying a switch-blade 81, whose 95 ends 82 project from opposite sides thereof. When the upper solenoid is energized, the switch-blade is carried upward with the core into engagement with the spring-clip contacts 83 84 and is frictionally held thereby to bridge 100 the space between the clips for the passage of current. A wire 85, leading from the brush 68^b of the ring connected with the small segment, is branched and connected to the coil of each of the lower solenoids 78, and from 105 the opposite ends of these coils wires 91 91^a lead to the clips 83 and thence to the speed-controlling solenoids 22 22^a, which are connected, as indicated at 93, with the wire 73 from the generator to the circuit-closer. The 110 upper switch-solenoids are connected in circuit with the generator and the speed-controlling solenoids in the following manner: Wires 87 87^a from the brushes of the rings 69^a 70^a connect directly with the coils of the upper 115 switch-solenoids 77. The opposite end of each coil is connected to a contact-piece in the form of a spring-clip 88, with which a gravity or spring actuated switch-arm 89 normally engages. These switch-arms are 120 pivoted in the clips 84 and serve to complete the circuit from the coil of the solenoid to the generator through the wire 90.

Let it now be assumed that the registering of the perforations of the master with the tracker-ducks does not coincide with the action of the punches and that an increase in the speed at which the master is being advanced

is necessary to restore exact synchronism. Under these conditions a power-pneumatic in responding would be prevented from performing its intended function of adjusting 5 the stop-bar, as the headed end of the punch would be projected into the recess thereof and tend to lock the same and prevent its full movement toward the right. There would be a partial adjustment of the stop-bar, however, 10 as shown at 42^a, Fig. 11, the relative proportions of the recess and punch-head being such as to allow for a movement of the bar sufficient to vibrate the contact-arms 61 and close the circuit. If now it is borne in mind 15 that contact between the small segment 68 and brush 71 occur simultaneously with the operation of the circuit-closer only under normal conditions, it follows, therefore, that under the conditions stated when the 20 circuit is closed as described one of the larger segments would be in contact with the brush 71, also that as an increase in speed is required the high-speed controller must be energized, and as it is thrown in circuit by the 25 switch 75 the circuit would be completed through the brush 70^b, ring 70^a, and segment 70. Consequently this segment would at such time be in contact with the brush 71, and current from the generator would flow by way 30 of wire 73 through the circuit-closers and wire 74 to the brush 71, thence to segment 70, ring 70^a, and by brush 70^b and wire 87^a to the upper solenoid of switch 75, the return being through clip 88, switch-arm 89, clip 84, 35 and wire 90 back to the generator. Thus far the speed-controller or brake-actuating solenoid 22 has not been energized nor included in circuit; but the flow of current has served to energize the upper solenoid 77 of the 40 switch 75, and as the core is drawn upward the projecting ends 82 of the switch-blade are forced into the spring-clips 83 84 and held thereby, and a projection 89^a on the core strikes and disengages the switch-arm 89 45 from the clip 88. This results in cutting out the solenoid 77, also the circuit-controller and circuit-closers and completes a new circuit from the generator through the wires 73 93 to the speed-controlling solenoid 22 50 and back to the generator by way of wire 91^a, clip 83, switch 81, clip 84, and wire 90. Being thus energized, the speed-controlling solenoid 22 draws in its core, and thereby through the lever 20 tightens the friction- 55 band brake around the gear 17, which, as above described, results in increasing the speed of rotation of the feed-roller over that of the driving-shaft 7, and consequently accelerates the feed of the master. This action 60 continues until exact synchronism is restored, and assuming this condition to be present it will be seen that as the circuit is again closed through the small segment 68 the lower solenoid 78 of the switch 75 will be energized, 65 and in drawing the core down will cut out

the high-speed controller. As the switch-arm 89 again bridges the space between the clips 84 88 normal conditions will be restored. The operation of the low-speed controller being identical, a detailed description is not 70 deemed necessary in view of the foregoing.

For the guidance of the performer in reproducing a musical composition on a mechanical player it is now customary to indicate on commercial rolls by a sinusoidal line 75 changes in tempo, such a line being plotted or determined by a skilled performer as the music-sheet passes through a player. In observing the changes indicated the performer is required to adjust a lever or other controlling device which involves considerable attention and effort on his part. I find that the same effect may be obtained automatically in the copies produced by the mechanism above described by using a commercial roll containing such tempo-marking as a master and varying the feed of the master manually in accordance with the tempo changes as represented by the sinusoidal line thereon and through the responsive action of the synchronizing mechanism producing such changes in the copies. Upon reproducing the musical composition with one of these copies in a mechanical player the desired tempo variations will occur without action on the part of the 95 performer.

It will be understood that I do not wish to limit myself to the exact construction and arrangement of mechanism herein shown and described, as various changes might be made 100 without departing from the spirit and scope of my invention. For example, I might dispense with the automatic mechanism employed in connection with the changeable-speed gearing and control the latter manually by employing an audible signal, such as is shown in Fig. 13, to sound at the instant the punches are in position to act or at every second, third, or fifth reciprocation of the punches, as a guide to an attendant, who by applying 105 pressure with the fingers to the friction-surface of the bevel-gears 17 and 18 could readily and effectively vary and control the feed of the master. Again, I may employ the changeable-speed gearing and its controlling 110 devices in connection with other apparatus, or with modifications of the present apparatus, or I may modify this gearing; but all such changes I consider obvious and immaterial variations of form and not of substance 115 and still within the meaning of the present invention.

Having therefore described my invention, I claim—

1. In a machine for duplicating music-rolls, 125 the combination of a music-sheet, devices responsive to the perforations therein, a series of unperforated sheets, mechanism co-operating with said sheets to reproduce in said sheets, the perforations of the master, and 130

automatic means for correlating the action of the responsive devices and the reproducing mechanism

2. In a machine for duplicating music-rolls, 5 the combination of a master-sheet, devices responsive to the perforations therein, a series of unperforated sheets, punching mechanism coöperating with said sheets to reproduce in said sheets and space in definite proportion, 10 the perforations of the master, and automatic means for correlating the action of the responsive devices and the reproducing mechanism.

3. In a machine for duplicating music-rolls, 15 the combination of a continuously-advanced master and its responsive devices, punching mechanism capable of acting periodically for reproducing the perforations of the master in the copies, and means for varying the feed 20 of the master to correlate the action of the responsive devices and the punching mechanism.

4. In a machine for duplicating music-rolls, the combination of the master and its responsive devices, continuously-acting feed mechanism for advancing the master, changeable-speed gearing coöperating to vary the feed, 25 punching mechanism for reproducing the perforations of the master in the copies, and means controlling the changeable-speed gearing to vary the feed as required for correlating the action of the responsive devices and the punching mechanism.

5. In a machine for duplicating music-rolls, the combination of the master and its responsive devices, continuously-acting feed mechanism for advancing the master, changeable-speed gearing coöperating to vary the feed, 35 punching mechanism for reproducing the perforations of the master and spacing the same in definite proportion in the copies, and means 40 for electrically controlling the changeable-speed gearing to correlate the action of the responsive devices and the punching mechanism.

45 6. In a machine for duplicating music-rolls, the combination of the master and its responsive devices, said devices comprising a tracker-board having two series of tracker-ducts registering in pairs with each perforation of 50 the master, a pneumatic coöperating with each tracker-duct, and a series of power-pneumatics communicating individually through separate passages with an exhaust-pressure chamber, each passage being controlled by a 55 pair of said pneumatics, together with a series of punches for reproducing the perforations of the master in the copies, and means operated by each power-pneumatic for controlling the action of one of the punches.

60 7. In a machine for duplicating music-rolls, the combination of the master and its responsive devices, feed mechanism for advancing the master, changeable-speed gearing for varying the feed, a series of punches coöperating with said responsive devices for repro-

ducing the perforations of the master in a copy-blank, means for continuously reciprocating the punches, and synchronizing mechanism controlling the changeable-speed gearing for correlating the action of the responsive devices and the reciprocation of the punches. 70

8. In a machine for duplicating music-rolls, the combination of the master and its responsive devices, feed mechanism for continuously 75 advancing the master, a series of punches coöperating to reproduce the perforations of the master in a copy-blank, feed mechanism for advancing the copy-blank a definite distance step by step, and means controlled by 80 the master for synchronizing the action of the responsive devices and the intermittent feed of the copy-blank.

9. In a machine for duplicating music-rolls, 85 the combination of the master and its responsive devices, feed mechanism for advancing the master, high and low speed controllers coöperating to vary the feed, punching mechanism for reproducing the perforations of the master, and synchronizing mechanism comprising means for closing an electric circuit on each action of the responsive devices of the master and means for directing the current to energize or cut out either the high or the low speed controller, to correlate the action 90 of the responsive devices and the punching mechanism.

10. In a machine for duplicating music-rolls, the combination of the master and its responsive devices, feed mechanism for advancing 100 the master, changeable-speed gearing coöperating to vary the feed, punching mechanism for reproducing the perforations of the master, and synchronizing mechanism comprising a source of electricity, a circuit-closer 105 actuated by said responsive devices, a circuit-controller, high and low speed controllers coöperating with the changeable-speed gearing and switches operated by the circuit-controller for cutting the speed-controllers in and 110 out of circuit, to correlate the action of the responsive devices and the punching mechanism.

11. A machine comprising a perforating mechanism, a controlled master-sheet device 115 responsive to the movements of said sheet, and means for automatically bringing the movements of the master-sheet and the movements of the perforating mechanism into synchronism. 120

12. A machine comprising a perforating mechanism, and controlling master-sheet therefor with the perforations therein in distorted relation to each other; and automatic means for correcting in the copies made by 125 the perforating mechanism the distortions in the master-sheet.

13. A machine comprising a perforating mechanism, a controlling master-sheet having perforations therein differing from those de- 130

sired to be reproduced in copies, devices responsive to said perforations, a series of unperforated music-sheets, mechanism for perforating said sheets, and means interposed 5 between said responsive means and perforating mechanism for automatically controlling the action of the perforating mechanism.

14. A machine comprising a perforating mechanism, a controlling master-sheet having 10 perforations therein differing from those desired to be reproduced in copies, devices responsive to said perforations, a series of unperforated music-sheets, mechanism for perforating said sheets, and means interposed 15 between said responsive means and perforating mechanism for automatically controlling the time intervals between the action of the perforating mechanism.

15. A controlling master-sheet with perforations therein having the distance between 20 the perforations multiples of various elements of length, and changeable-speed gearing for varying the relative movements of the master-sheet with respect to the movements of the 25 perforating mechanism for producing perforations in the copies, the distances between which are multiples of one fixed element of length.

16. A machine comprising a perforating 30 mechanism, and a controlling master with perforations therein, the longitudinal distance between them being longer or shorter than the distance the paper is fed in one complete perforating movement of the mechanism; and 35 changeable-speed gearing for changing the relative speed of the controlling master-sheet and the paper as it passes through the perforating mechanism, thereby producing in the copies perforations the distance between which 40 is a multiple of the distance the paper is fed through the perforating mechanism in one operation.

17. A machine comprising a perforating mechanism, a controlling master-sheet therefor, the perforations therein having a variable 45 length between the successive perforations therein, and means controlled by the master-sheet for changing the relative speed of the master-sheet to the perforating mechanism in 50 proportion to said variations.

18. A machine comprising a perforating mechanism, a distorted master-sheet therefor, and means for changing the relative speed of the master-sheet to that of the perforating 55 mechanism in proportion to the distortions in the master-sheet.

19. A machine comprising a perforating mechanism and a controlling perforated master-sheet therefor, a driving mechanism for the 60 master-sheet, a responsive device to the perforations in the master-sheet, a driving mechanism for sheets to be perforated, and variable-speed gearing controlled by the master-sheet for changing the relative speed of the 65 said driving mechanism.

20. A machine comprising a perforating mechanism and a controlling perforated master-sheet therefor, a driving mechanism for the master-sheet, a responsive device to the perforations in the master-sheet, a driving mechanism for sheets to be perforated, and automatic means for changing the relative speed of the said driving mechanism. 70

21. A machine comprising a perforating mechanism, a controlling perforated master-sheet therefor, a driving mechanism for the master-sheet, a responsive device to the perforations in the master-sheet, a driving mechanism for sheets to be perforated, and automatic means controlled by the master-sheet 80 for changing the relative speed of the driving mechanism.

22. A machine comprising a perforating mechanism, a controlling perforated master-sheet therefor, a driving mechanism for the 85 master-sheet, a responsive device to the perforations in the master-sheet, a driving mechanism for sheets to be perforated, and a variable-speed device for changing the relative speed of the said driving mechanism at different 90 places along the sheet.

23. A machine comprising a perforating mechanism, a controlling perforated master-sheet therefor, a driving mechanism for the master-sheet, a responsive device to the perforations in the master-sheet, a driving mechanism for sheets to be perforated, and a variable-speed device for changing the relative speed of the driving mechanism at various 95 times during the feeding of the sheet. 100

24. A machine comprising a perforating mechanism, a controlling means for said mechanism whose movements are not timed to the movements of the mechanism, and means for automatically bringing the controlling means 105 and the perforating mechanism into synchronism with each other.

25. A machine comprising a perforating mechanism, a controlling perforated master-sheet therefor, and means for changing the 110 speed of the master-sheet with respect to the perforating mechanism while the sheet is in motion.

26. A machine comprising a perforating mechanism, a controlling perforated master-sheet therefor, and automatic means for varying 115 the speed of the master-sheet.

27. A machine comprising a perforating mechanism, a controlling master-sheet therefor, and a variable-speed driver for said master-sheet. 120

28. A machine comprising a perforating mechanism, a controlling master-sheet therefor, a driving mechanism, and an automatic speed-changing device for said sheet. 125

29. A machine comprising a series of punches, a series of means throwing certain of said punches into and out of action, a controlling means for said action of the punches in time with its movements to the same, and 130

means for automatically bringing the movements of the controlling means and the perforating mechanism into synchronism with each other.

5 30. A machine comprising a series of punches, a controlling perforated master-sheet, a series of means throwing certain of the punches into and out of action responsive to the perforations in the master-sheet, the movements of the master-sheet not being timed to the movements of the punches, and means for automatically bringing them into synchronism with each other.

15 31. A machine comprising a series of punches, a pneumatic means throwing certain of said punches into and out of action, the said pneumatic means not being timed in its action to the movement of the punches, and means for automatically bringing them into synchronism with each other.

20 32. A machine comprising a series of punches, a series of controllers for throwing certain of the punches into and out of action, a perforated master-sheet to the perforations of which the controllers respond, and automatic means for changing the speed of the master-sheet during its travel.

25 33. A machine comprising a series of punches, a series of controllers for throwing certain of the punches into and out of action, a perforated master-sheet to the perforations of which the controllers respond, and automatic means for varying the speed of the master-sheet.

30 34. A machine comprising a series of punches, a series of controllers for throwing certain of the punches into and out of action, a perforated master-sheet to the perforations of which the controllers respond, and a variable-speed driver for said master-sheet.

35 35. A machine comprising a series of punches, a series of controllers for throwing certain of the punches into and out of action, a perforated master-sheet to the perforations of which the controllers respond, and an automatic speed-changing device.

40 36. A machine comprising a perforated master-sheet, a tracker-board having two tracker-ducks opened by each perforation therein, a pair of pneumatic valves in series relation connected to the tracker-ducks, a series of power-pneumatics controlled by the pneumatic valves, a series of punches thrown into action by the power-pneumatics, and means for automatically bringing the movements of the perforations in the master-sheet from the tracker-ducks into synchronism with the movements of the punches.

45 37. A machine comprising a perforated master-sheet, a tracker-board having two tracker-ducks opened by each perforation therein, a

pair of pneumatic valves in series relation connected to the tracker-ducks, a series of power-pneumatics controlled by the pneumatic valves, a series of punches thrown into action by the power-pneumatics, and means for automatically changing the speed of the master-sheet during its travel.

50 38. A machine comprising a perforated master-sheet, a tracker-board having two tracker-ducks opened by each perforation therein, a pair of pneumatic valves in series relation connected to the tracker-ducks, a series of punches thrown into action by the power-pneumatics, and means for automatically changing the speed of the master-roll.

55 39. A machine comprising a perforated master-sheet, a tracker-board having two tracker-ducks opened by each perforation therein, a pair of pneumatic valves in series relation connected to the tracker-ducks, a series of punches thrown into action by the power-pneumatics, and a variable-speed driver for said master-sheet.

60 40. A machine comprising a perforated master-sheet, a tracker-board having two tracker-ducks opened by each perforation therein, a pair of pneumatic valves in series relation connected to the tracker-ducks, a series of punches thrown into action by the power-pneumatics, and an automatic speed-changing device.

65 41. A machine comprising a perforated master-sheet, a tracker-board having two ducts therein for each line of possible perforations in the sheet, a pair of pneumatic valves connected to the pairs of tracker-ducks, a series of power-pneumatics controlled by said valves, a driver for the master-sheet, a perforating mechanism thrown into action by the power-pneumatics, and means in said driver whereby the perforations in the master-sheet opens its pairs of tracker-ducks at such time as the punches can respond thereto.

70 42. A machine comprising a perforated master-sheet, a tracker-board having two ducts therein for each line of possible perforations in the sheet, a pair of pneumatic valves connected to the pairs of tracker-ducks, a series of power-pneumatics controlled by said valves, a driver for the master-sheet, a perforating mechanism thrown into action by the power-pneumatics, and means in said driver whereby the perforations in the master-sheet opens its pairs of tracker-ducks in synchronism with the movements of the perforating mechanism.

In testimony whereof I affix my signature in the presence of two witnesses.
